(57) CLAIM

The ornamental design for a base for a personal full body therapy compartment, as shown and described.

DESCRIPTION

FIG. 1 is a front perspective view of a base for a full body therapy compartment, embodying our new design, the broken line showing is for illustrative purposes only and forms no part of the claimed design;

FIG. 2 is a top plan view thereof;

FIG. 3 is a right side view thereof;

FIG. 4 is a left side view thereof;

FIG. 5 is a bottom plan view thereof;

FIG. 6 is a front view thereof; and,

FIG. 7 is a rear view thereof.
